MECHANISM FOR PRODUCING CURVED
METAL ARTICLES

Robert Körting, Kochstedt, Germany, assignor to
Junkers Flugzeug-und-Motorenwerke Aktien-
gesellschaft, Dessau, Germany

Application April 9, 1938, Serial No. 201,086
In Germany May 31, 1937

3 Claims. (Cl. 153—2)

My invention relates to the production of curved sheet metal articles and more especially curved channels, or other profilated sheet metal strips of open cross-section. It has particular reference to the means for producing these articles. It is an object of my invention to provide means which enable such sheet metal articles to be produced in a particularly economical and technically perfect manner.

In bending machines as hitherto suggested, in which the workpiece is carried, together with an oscillatable templet, past a fixed abutment to curve it in accordance with the shape of the templet, an altogether satisfactory bending of such profilated strips is not always possible. Difficulties are encountered more especially if articles shall be produced which possess a cross-section of considerable height relative to the bending radius.

According to this invention profilated strips, the satisfactory bending of which without creasing presents difficulties, for instance strips of Z-like cross-section to be bent on edge, are produced by first bending, in a known manner, with the aid of a templet a strip of a different, readily bendable cross-section, forming an intermediate product, part of which equals the cross-section of the strip to be produced. The profilated rod or strip thus obtained is then cut longitudinally into two or more parts, one or all of which constitute the profilated product desired. A particularly favorable mode of proceeding includes the production of an intermediate product, the cross-section of which is composed of the symmetrically arranged cross-sections of a pair of strips which constitute the final product, so that by cutting the intermediate product in two parts two symmetrically equal products are obtained. A cutting device such as required for this purpose may consist of one or a plurality of circular saws arranged, in juxtaposition or in series, in different planes, these saws being mounted on the bed of the bending machine for adjustment in such manner that they will cut the intermediate product in two halves, while it is still being bent or after it has been bent.

In order that during the cutting step the saw always cuts the metal to a favorable depth also if the workpiece is formed with an irregular curvature, so as to avoid an interruption of the cutting action at such points of the workpiece, at which greater changes of curvature occur, I may arrange the cutting device on a movable carrier which is constantly forced towards the work piece (for instance by arranging it on a rock

arm under spring action) this carrier being provided with a spacing roller or the like applied against the sheet metal body to be cut and thereby holding the cutting device in the correct position relative to the workpiece.

In the drawing affixed to this specification and forming part thereof some embodiments of a bending and cutting device according to my invention are illustrated diagrammatically by way of example.

In the drawing—

Fig. 1 is a plan view of a combined bending and cutting device, the bending being effected with the aid of a segment arranged for rocking movement.

Fig. 2 is a cross-section on the line II—II and Fig. 3 is a similar view on the line III—III in Fig. 1.

Fig. 4 is a plan view of a bending and cutting device comprising a bending templet of irregular shape.

Fig. 5 is a cross-section, on the line V—V in Fig. 4, of the templet and the sheet metal body to be curved.

25 Figs. 6 to 8 are perspective views of parts of bent profilated strips, which allow producing the final products illustrated by the cross-sections shown in Figs. 6a, 7a and 8a, respectively.

If it is for instance intended to produce a sheet metal channel of sickle-like cross-section such as shown in Fig. 6a, I first produce, by folding a sheet metal strip or in some other way, a straight tube having a cross-section such as shown in Fig. 6 and I then bend it in a bending device 30 to produce the curved shape according to Fig. 6.

A bending device adapted for use in such a case is shown in Figs. 1 to 3. 1 is a table or bed plate and 3 is a segment-shaped templet mounted for oscillation about a journal 2 extending across the table 1 and carrying, on the other side of the table, a gear 8 meshing with another gear 9, which may be driven by suitable means (not shown). 6 is an arm keyed on the journal or shaft 2 and carrying at its free end an eccentrically mounted clamping roller 7 serving to clamp the straight tube 4 to the templet 3. If the journal or shaft 2 is now rotated in the direction of the arrow a, the arm 6 and the templet 3 are rocked in the same direction. The tube 4, being prevented by a roller 10 mounted on the table 1 from following this rocking movement is forced to apply itself against the curved surface of the segment 3 and to be thus bent into contact with this surface.

55 After having thus been curved, the tube 4 is

now placed in the cutting device mounted also on the table 1 and consisting of a guide roller 12 and a circular saw 13 mounted for rotation in a sliding block 14 which can be adjusted in guides 15 mounted on the plate 1 by means of the hand wheel 16 and spindle 17. The circular saw 13, which may be set rotating for instance by means of a flexible shaft 18, is so adjusted relative to the roller 12 that it cuts the curved tube 4 placed on the roller 12 in the longitudinal direction as shown in Fig. 6, so that two curved channels of symmetrical cross-sections such as shown in Fig. 6a are formed.

In order to be able to bend profiled strips which can be bent only with difficulty, according to an irregular curve, for instance a curve other than a circle, I may employ a bending device such as illustrated in Fig. 4. Here the straight sheet metal channel 40 is fixed by means of a strap 21 to a curved templet 23 and drawn, together with the templet, through between two abutments 25 and 26 mounted on the table 41. The abutment 25 is formed by a roller rotatably mounted on a journal 28 and supporting the templet 23. The abutment 26 is a block formed in accordance with the cross-section of the outside of the channel 40 and applying itself against this channel. On being drawn past the block 26 the channel 40 is continuously forced down onto the curved templet 23 and is thereby bent accordingly.

If it is for instance desired to produce profiled strips, curved on edge of Z-shaped cross-section such as shown in Fig. 7a, I first produce a channel, for instance of the kind shown in Fig. 7, which can be bent more easily and can thereafter be cut in two parts, each possessing the desired cross-section of the final product. On the intermediate product of Fig. 7 having been bent by means of a bending device such as shown in Fig. 4, the templet 23 together with the curved intermediate product 41 is passed once more between the two abutments 25 and 26, however in the opposite direction and a cutter such as the circular saw 43 is made to act on the intermediate product along the middle line indicated in Fig. 7. The saw 43 is here mounted for rotation on the arm 36 arranged for rocking movement about the pin 35. On the axle carrying the saw is also mounted a spacing disk or roller 37, which is acted upon by a coil spring 38 and applied against the curved rod 40, thereby causing the saw to cut the sheet metal body to uniform depth. The rock arm 36 can be temporarily fixed in its position in the block 26 by means of a bolt or screw 39. The curved templet 23 is preferably formed with a groove 29, which the saw may enter.

Preferably the cross-section of the intermediate product is so chosen that all the parts of the intermediate product severed by cutting are fit for subsequent use. In order to produce for instance channels curved on edge as shown in Fig. 8a, I may for instance bend a channel such as shown in Fig. 8 having a cross-section which resembles that of a pair of symmetrically arranged channels of the kind shown in Fig. 8a. On this channel being cut through lengthwise along three lines indicated in Fig. 8, two sym-

metrically equal rods 31 and 32 having a cross-section such as shown in Fig. 8a and two angle strips 33, 34 are obtained.

I wish it to be understood that I do not desire to be limited to the exact details of construction shown and described for obvious modifications will occur to a person skilled in the art.

I claim:

1. Mechanism of the class described comprising, in combination, an abutment, a second abutment spaced therefrom and having a face shaped to the cross-sectional shape of the metal strip to be bent, a curved bending templet having one face cooperable with the face of said shaped abutment, a circular saw positioned adjacent the passage between said abutments in longitudinally offset relation thereto, the face thereof lying in a plane substantially parallel to that in which the abutments lie, means for moving the periphery of said saw toward and away from the line of passage, and means for passing said templet together with the sheet metal strip in either direction between said abutments whereby the latter may be bent in conformity with the templet curve during passage in one direction and severed longitudinally by the adjusted saw on its return passage.
2. Mechanism of the class described comprising, in combination, an abutment, a second abutment spaced therefrom and having a face shaped to the cross-sectional shape of the metal strip to be bent, a curved bending templet having one face cooperable with the face of said shaped abutment, a circular saw positioned adjacent the passage between said abutments in longitudinally offset relation thereto, the face thereof lying in a plane substantially parallel to that in which the abutments lie, means for moving the periphery of said saw toward and away from the line of passage, and means for passing said templet together with the sheet metal strip in either direction between said abutments whereby the latter may be bent in conformity with the templet curve during passage in one direction and severed longitudinally by the adjusted saw on its return passage.
3. Mechanism of the class described comprising, in combination, an abutment, a second abutment spaced therefrom and having a face shaped to the cross-sectional shape of the metal strip to be bent, a curved bending templet having one face cooperable with the face of said shaped abutment, a circular saw positioned by one of said abutments adjacent the passage therebetween in longitudinally offset relation thereto, the face thereof lying in a plane substantially parallel to that in which the abutments lie, means for moving the periphery of said saw toward and away from the line of passage, and means for passing said templet together with the sheet metal strip in either direction between said abutments whereby the latter may be bent in conformity with the templet curve during passage in one direction and severed longitudinally by the adjusted saw on its return passage.

ROBERT KÖRTING.
